MAIL HANDLING APPARATUS

Albert James Clayton, Dalton, Mo.

Application February 12, 1948, Serial No. 7,883

1 Claim. (Cl. 258—22)

1

This invention relates to mail delivering and receiving means.

An object of this invention is to provide an improved pick-up means whereby a moving mail car may pick up a bag or receptacle which is releasably supported at one side of the track.

Another object of this invention is to provide an improved holder for a mail bag or like receptacle which includes a standard having a horizontally swinging arm which is spring-pressed to an inoperative position parallel with the track, and is held in operative position at right angles and extending toward the tracks by means of a weighted trigger which is engaged by the bag or receptacle, so that when the bag or receptacle is picked up by the pick-up member on the mail car, the trigger will be released and the supporting arm will swing outwardly to inoperative position.

A further object of this invention is to provide an improved pick-up member for mounting on a mail car which includes a pivoted arm having one or more U-shaped holders on the outer end thereof, with a latch element swingable across the sides of the holder so as to lock the bag or receptacle in the holder.

A further object of this invention is to provide an improved ejector swingably mounted on the mail car and spring-pressed to ejecting position, the ejector being latched in inoperative or loading position so that when the latch is released the ejector will spring outwardly and throw the bag or receptacle outwardly through the open door.

A further object of this invention is to provide an improved container or receptacle for either the loose mail or the mail bag, which is particularly designed for use with the pick-up structure herein disclosed.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a plan view of a mail delivering and receiving means constructed according to an embodiment of this invention showing the receiving and ejecting means mounted on a mail car which is shown in horizontal section.

Figure 2 is a sectional view taken on the line 2—2 of Figure 1.

2

Figure 3 is a sectional view taken on the line 3—3 of Figure 1.

Figure 4 is a sectional view taken on the line 4—4 of Figure 2.

5 Figure 5 is a fragmentary plan view, partly in section and taken substantially on the line 5—5 of Figure 2, of the receiver mounted on the mail car.

10 Figure 6 is a fragmentary sectional view taken substantially on the line 6—6 of Figure 2, showing the receiver with a receptacle disposed therein.

Figure 7 is a fragmentary sectional view taken on the line 7—7 of Figure 3.

15 Figure 8 is a fragmentary sectional view taken on the line 8—8 of Figure 1, showing the ejector.

Figure 9 is a fragmentary sectional view taken on the line 9—9 of Figure 1.

20 Referring to the drawings, the numeral 10 designates generally a mail car which is formed with a door opening 11 in the side wall 12 thereof. In order to provide a means whereby mail may be picked up by the moving car 10, I have provided a holder which is adapted to be mounted 25 beside the track. The holder, generally designated as 13, comprises a lower standard member 14 of tubular construction having a base 15 at the lower end thereof which is secured by fastening means 16 to a stationary support. The lower standard member 14 has rotatably mounted therein an elongated upper standard member 17 which at its lower end telescopes into the lower standard member 14. The lower standard member 14 at its upper end is formed with an annular flange 18 and the upper or rotatable standard member 17 is formed with a flange 19 bearing against the flange 18.

25 A coil spring 20 is disposed within the tubular lower standard 14 engaging about the rotatable standard 17 and the spring 20 is secured at one end as at 21 to the lower standard member 14 and is secured at the other end as at 22 to the upper standard member or shaft 17. The spring 20 is provided so that the upper standard member 17 or shaft will normally be rotated to a position wherein the bag or container supporting means to be hereinafter described will be normally disposed substantially parallel with the tracks. The upper member 17 has fixed thereto a right angularly extending bracket arm 23 which at its outer end is formed with an enlarged plate 24.

30 A trigger, generally designated as 25, is rockably carried by the bracket arm 23 and includes an elongated bar 26 which is pivoted as at 27 to a depending lug 28 fixedly carried by the bracket

arm 23. The upper or outer end of the arm 26 has secured thereto a plate 29 which is adapted when in set or operative position to be disposed substantially coplanar with the plate 24. The inner end of the arm 26 has fixed thereto a weight 30 and the standard member 14 adjacent the upper end thereof is formed with a slotted keeper 31 which is engageable by the upper portion of the weight 30 so that when the arm or trigger 25 is in operative or set position the rotatable standard or shaft 17 will be locked in a position at right angles to the rail or track.

The upper member or shaft 17 also has fixed thereto a right angularly disposed resilient arm 32 formed at its outer end with a clamping plate 33 which is adapted to engage the upper end of a container 34 which is seated at its lower end on the two plates 24 and 29. The container 34 includes a pair of telescopically arranged members 35 and 36 with the latter member having extending oppositely and diametrically a pair of L-shaped bracket arms 37.

The bracket arms 37 are formed with downturned outer sides 38, the purpose for which will be hereinafter described. The container 34 is adapted to receive either loose mail or mail in a bag and the container 34 is adapted to be removed from the supporting structure at one side of the track by means of a catcher generally designated as 39. The catcher 39 includes a pair of vertically spaced apart U-shaped members 40 and 41 which are connected together at their bights by means of a connecting bar 42.

The U-shaped members 40 and 41 are carried by a pivoted arm 43 which is formed with an offset intermediate portion 44 and the inner end of the arm 43 is pivoted as at 45 on a bearing or support 46 which is secured to the inner side of the side wall 12 of the car 10. An elongated coil spring 47 is secured as at 48 to the outer portion of the arm 43 and is secured as at 49 to the inner side of the side wall 12 of the car 10. The spring 47 engages about the hinged portion of the arm 43 as shown in Figure 1 and is adapted to normally urge the arm 43 to swing inwardly within the interior of the car 10. A handle 50 is fixed to the arm 43 adjacent the inner portion thereof and is adapted to be held by a person standing adjacent the opening 11 to manually retain the arm 43 in mail receiving position projecting outwardly through the opening 11. The arm 43 is also provided adjacent the outer portion thereof with a bracing bar 51 having an obtusely disposed inner end portion 52 engageable against the outer side of the side wall 12 so that the arm 43 will be firmly braced and held against bending under impact occasioned by the catcher initially striking the stationary container 34.

In order to provide a means whereby the container 34 will be automatically latched to the receiver, the upper U-shaped member 40 is provided with a spring-pressed latching bar 53 which is pivoted on a pivot 54 carried by one arm of the upper U-shaped member 40. The latching member 53 includes a lug 55 which is engaged by a spring 56 carried by the U-shaped member 44 and the spring 56 is adapted to normally maintain the latching member 53 in outwardly extended position or in inwardly projected and latching position across the free ends of the U-shaped member 40. A trigger or trip member 57 is formed integral with the latching member 53 and is adapted when the latching member 53 is in outwardly extended position to be disposed substantially across the open ends of the sides of the U-shaped mem-

ber 40 as shown in Figure 5 in order that when the container 34 moves between the parallel sides of the two U-shaped members 40 and 41, the trip member or latch operator 57 will be swung inwardly and will thereby swing the latching member 53 across the open end of the upper U-shaped member 40. When the container 34 is caught by the catcher 39, the L-shaped arms 31 of the container 34 will ride over the upper member 40 so that the container 34 will be suspendingly supported by the upper U-shaped member 40.

When the latch member 53 is in latching position holding the container 34 against forward movement, the handle 50 may be released so that the catcher 39 may be swung inwardly into the car 10 under the tension of spring 47. When it is desired to eject a container or mail bag from the car 10 through the door opening 11, the container or mail bag is engaged with an ejector generally designated as 58. The ejector 58 includes an elongated bar or plate 59 which is hingedly secured as at 60 to a base plate 61 and the latter is secured by fastening means 62 to the inner side of the side wall 12. The ejector 58 also includes pairs of right angularly disposed arms 63 between which the container or mail bag is adapted to engage. The ejector 58 is preferably disposed closely adjacent the floor 64 of the mail car and a spring 65 constantly urges the ejector 58 to swing outwardly toward ejecting position. The ejector 58 may be latched in its inner inoperative position by means of a spring-pressed latching member 66 which is secured to a bearing for mounting 67 and the latter is secured to the floor 64 of the car 10. The latching member 66 includes an upwardly offset handle or operator 68 which may be raised when the ejector is to be swung outwardly to ejecting position under the tension of spring 65.

In the use and operation of this device when it is desired to deliver mail from a station to a moving car, the mail is placed in the container 34 and the latter is mounted on the bracket 23 resting on the plates 24 and 29 and with the spring arm 32 bearing against the upper end of the container. The trigger 25 is held in its upper latching or locking position when the container 34 is between the bracket 23 and the bracket arm 32. The bracket 23 and shaft 17 are swung outwardly against the tension of spring 20 to a position substantially at right angles to the tracks. A weight 30 is engaged with the keeper 31 so that when the container 34 is in receiving position the shaft or upper standard member 17 will be latched in its delivering position. When the mail car 10 approaches the station the catcher 39 is manually swung outwardly to receiving position as shown in full lines in Figure 1 and at this time the latching member 53 is swung outwardly with the trip member 57 extending across the open ends of the upper U-shaped member 40. The container 34 will strike the tripping member 57 thereby swinging the latching member 53 inwardly across the open ends of the upper U-shaped member 40 of the catcher so that the container 34 will be firmly latched in the catcher 39. The container 34 will be held against dropping through the catcher 39 by means of the inverted L-shaped members 37 which engage over the upper U-shaped member 40. As soon as the container 34 has been removed from the bracket arm 23, the trigger 25 will swing downwardly and outwardly under the action of the weight 30 so that the shaft 17 may rotate through an arc of substantially 90° with

the bracket arm 23 and the upper arm 32 substantially parallel with the line of the tracks.

When it is desired to eject mail in a bag or container from the car 10, the bag or container is engaged between arms 63 of the ejector 58. The latch member 66 is released at the proper moment so that the ejector 58 will be swung outwardly, thereby throwing the mail bag or container onto the platform or in a position adjacent the platform.

I claim:

A mail receiving means for attachment to a mail car and extendable from an inoperative position within the car to an operative position extending from the side of the car, said means comprising a horizontally swingable elongated arm, a spring extending from an outer point on said arm to an interior point of said car biasing said arm to inoperative position, means for holding said arm against the bias of said spring, U-shaped catcher means carried by the outer end of said arm, and latch means carried by said catcher means for releasably locking a mail container in said catcher means, said latch means comprising an elongated member pivotally carried by the outermost arm of said catcher means adjacent its outer extremity, an operating lever carried by and extending oppositely from said elongated member, said lever extending between

the open end of said catcher means when in set position and adapted upon inward movement of a mail container to swing said elongated member transversely across the open end of said catcher so as to thereby lock said container in said catcher, a spring biasing said elongated member outwardly of said outermost arm and latching means carried by said first mentioned latch means for holding the latter against the bias of said last mentioned spring.

ALBERT JAMES CLAYTON.
